UNITED STATES PATENT OFFICE.

GEORGE R. BOWEN, OF SAN ANTONIO, TEXAS.

DESIGN FOR A HANDKERCHIEF, &c.

SPECIFICATION forming part of Design No. 25,753, dated July 7, 1896.

Application filed October 18, 1895. Serial No. 566,148. Term of patent 31 years.

To all whom it may concern:

Be it known that I, GEORGE R. BOWEN, a citizen of the United States, residing at San Antonio, in the county of Bexar and State of Texas, have invented a new and original Design for Handkerchiefs, Napkins, Fans, &c., of which the following is a specification.

This invention relates to a new and original design for handkerchiefs, fans, napkins, cards, and similar articles, and it has for its object to provide a design of this character that shall be both useful and ornamental.

The leading feature of the design resides in a large rectangular space having centrally arranged therein a circularly-shaped figure confining within the outlines thereof the representation of a woman's head having a coronet thereon; the representation of an eagle with outspread wings disposed in the space above the central circular figure and having grasped in the claws of one foot a bunch of arrows, and in the claws of the other foot a twig; a wreath-like figure partly encircling the representation of the eagle and disposed below the same; the representations of two men disposed in the space below the central circular figure, one of the men being represented as holding in one hand an upright pitchfork, and having the other hand grasped by the two hands of the other man; the representation of a woman at one side of the central circular figure, said woman being represented as being blindfolded and holding in one hand a sword, and in the other hand a pair of scales, and, at the opposite side of the central circular figure, the representation of a woman holding in an elevated position with one hand a scroll, and holding with the other hand a spear supporting on one end of its pole a cap; the representation of a pair of oppositely-disposed unfurled flags arranged within each corner of the large rectangular space and having their staffs crossed at a point intermediate of their ends, and a series of star-shaped figures scattered throughout the plain portions of the large rectangular space.

In the drawing the figure represents a face view of the design contemplated by this invention.

Referring to the drawing, the numeral 1 designates a large rectangular figure or space bounded by a wide marginal border 2, and located centrally within the figure or space 1 is a circular figure 3, within the outlines of which figure is represented a woman's head 4, having a coronet 5 thereon. In the space directly above the central circular figure 3 is the representation of an eagle 6 with outspread wings and having grasped by the claws of one foot a bunch of arrows 7 and by the claws of the other foot a twig 8. A wreath-like figure 9 partly encircles the representation of the eagle and is disposed below the same. In the space directly below the central circular figure 3 are the representations of two men 10 and 11, respectively, the man 10 being represented as holding in one hand an upright pitchfork 12 and having the other hand grasped by the two hands of the man 11.

At one side of the central circular figure 3 is represented the figure of a woman 13, blindfolded and holding in one hand a sword 14, and in the other hand a pair of scales 15, and at the side of the figure 3 opposite to the figure 13 is represented the figure of a woman 16, holding in an elevated position with one hand a scroll 17, and holding with the other hand a spear 18, which supports at one end of its pole a cap 19. In each of the corners of the large rectangular space 1 is represented a pair of oppositely-disposed unfurled flags 20, having their staffs 21 crossed at a point intermediate of their ends, and the design is completed by a series of star-shaped figures 22, scattered throughout the plain portions of the rectangular space 1.

What I claim is—

The design for handkerchiefs, fans and similar articles herein shown and described.

In testimony that I claim the foregoing as my own I have hereto affixed my signature in the presence of two witnesses.

GEO. R. BOWEN.
